CLAIM

I claim the ornamental design for a faucet, as shown and described.

DESCRIPTION

FIG. 1 is a perspective view of a first embodiment of a faucet;

FIG. 2 is a front view of FIG. 1;

FIG. 3 is a rear view of FIG. 1;

FIG. 4 is a side view of FIG. 1;

FIG. 5 is another side view of FIG. 1;

FIG. 6 is a top view of FIG. 1;

FIG. 7 is a bottom view of FIG. 1;

FIG. 8 is a perspective view of a second embodiment of a faucet;

FIG. 9 is a front view of FIG. 8;

FIG. 10 is a rear view of FIG. 8;

FIG. 11 is a side view of FIG. 8;

FIG. 12 is another side view of FIG. 8;

FIG. 13 is a top view of FIG. 8; and,

FIG. 14 is a bottom view of FIG. 8.

The broken lines shown in the drawings illustrate portions of the faucet that form no part of the claim. Broken lines formed of unequal length dashes (i.e., dash-dot) define bounds of the claimed design. Some portions of the faucet are shown with a symbolic break in their length. The appearance of any portion of the faucet between the break lines forms no part of the claim.
